(57) **CLAIM**

The ornamental design for a baby gym, as shown and described.

DESCRIPTION

FIG. 1 is a front, top perspective view of a baby gym, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another front, top perspective view of the baby gym, shown in an alternate position;

FIG. 10 is another front, top perspective view of the baby gym, shown in an alternate position; and,

FIG. 11 is rear, bottom perspective view thereof, shown in an alternate position.

The broken lines in the figures illustrate portions of the baby gym that form no part of the claimed design.

1 Claim, 11 Drawing Sheets
